UNITED STATES PATENT OFFICE

2,233,287

SMOKING PIPE

Arthur B. Modine, St. Petersburg, Fla.

Application September 2, 1933, Serial No. 228,074

13 Claims. (Cl. 131—198)

This invention relates to smoking pipes, and among other objects, is intended to provide a novel construction and arrangement whereby a cool, dry smoke may be obtained.

5 Another object of the invention is to provide novel means whereby air may be mixed with the smoke after leaving the bowl and before being taken from the discharge end of the stem.

Another object of the invention is to provide 10 automatically actuated means for controlling the admission of air to the smoke duct between the pipe bowl and the discharge end of the stem.

Another object of the invention is to provide a 15 novel arrangement whereby the automatically actuated means for controlling the admission of air to the smoke duct may be rendered ineffective for that purpose, if so desired, and at the will of the user.

Another object of the invention is to provide 20 thermostatically actuated means for automatically controlling the admission of air to the smoke duct.

Another object of the invention is to provide 25 a novel construction and arrangement wherein the thermostatically actuated means for controlling the admission of air to the smoke duct is effected directly by the temperature of the smoke within the duct, and is fully protected against the influence of any variation in atmospheric 30 temperature outside the smoke duct.

A further object of the invention is to provide an air cooled pipe having suitable moisture retaining means therein.

A still further object of the invention is to improve 35 devices of the character described in sundry details hereinafter referred to and particularly pointed out in the appended claims.

One embodiment of the present invention is shown for illustrative purposes in the accompanying drawing in which:

Fig. 1 is an enlarged elevational view, partly in section, of a smoking pipe embodying features of the present invention;

Fig. 2 is a fragmentary perspective view of a 45 portion of the structure illustrated in Fig. 1;

Fig. 3 is a further enlarged transverse sectional view taken substantially as indicated by the line 3—3 of Fig. 1;

Fig. 4 is an enlarged transverse sectional view 50 illustrating a portion of the structure shown in Fig. 1, and taken substantially as indicated by the line 4—4 thereof; and

Fig. 5 is a transverse sectional view similar to Fig. 3 showing certain of the parts in relatively 55 changed position, and illustrating the manner of

rendering the automatically actuated means ineffective to admit air to the smoke duct.

This invention is, in part, an improvement on the smoking pipe of my co-pending application, Serial No. 118,238, filed December 30, 1936, and in the illustrative embodiment shown in the drawing, the present invention comprises a bowl 8 having a stem associated therewith and indicated, as a whole by the numeral 9, the said stem being shown, in the present instance, as comprising a portion 11 formed integrally with the bowl 8 and having a smoke duct or chamber 12 formed therein adapted to communicate at one of its ends through a passage 13 with the interior of the bowl 8, and provided at its opposite end 15 with an open end portion adapted to receive a mouth piece indicated, as a whole, by the numeral 14 shown, in the present instance, as comprising the outer or discharge end portion 15 and an inwardly extending portion 16 of reduced diameter 20 adapted to be positioned within the open end portion of the stem 11 with a degree of snugness capable of retaining the mouth piece 14 against accidental displacement with respect to the stem 11, but free to be rotated manually with respect 25 thereto if so desired, the mouth piece 14 including also an elongated extension or finger 17 extending into the chamber 12, preferably, in spaced relation to the walls thereof, and shown, in the present instance, as a tubular member positioned 30 substantially in line with and forming an extension of an elongated passage 18 formed in the mouth piece.

The finger 17 is shown, in the present structure, as provided on one side thereof with a cut-away portion forming an elongated opening 19 through which smoke from the chamber 12 may enter the passage 18 of the mouth piece, and is provided, preferably, at its opposite side portion with a plurality of apertures 21 through which 40 moisture may drain or escape from the member 17 into the chamber 12 where it may be retained, thereby providing a dry smoke for the user free from condensate or other moisture.

For admitting air to the chamber 12 for cooling 45 purposes, the stem 11, preferably, adjacent the open end portion thereof is provided with an intake port or opening 22, and for automatically controlling the admission of air through the port 22, a thermostatic element 23 shown, in the present instance, as of the well known laminated type, consisting of two layers of different metals having relatively different co-efficients of expansion, is positioned, preferably adjacent the cut-away portion or elongated opening 19 of the 50 55

finger 17, and is secured adjacent one of its end portions, preferably, to the inner end portion of the finger 17, as indicated at 24, and provided adjacent its opposite end with a valve portion 5 25 extending into a recess 26 formed in the portion 16 of the mouth piece 14, and adapted, normally, to cover the intake port 22, as clearly illustrated in Figs. 1 and 3, in a manner to prevent the admission of air therethrough.

10 It will be apparent, however, that by reason of the arrangement shown and described, when the heat of the smoke in the chamber 12 is sufficient to actuate the thermostat 23, the valve portion 25 thereof will be moved away from or out of operative relation or closed position with respect to the intake port 22, to substantially the position illustrated by dotted lines in Fig. 1, and in proportion to the effect of the heat on the thermostat, thereby permitting air to enter through the 20 port 22 and mix with the smoke passing to the mouth piece 14, thus adding a cooling medium to the smoke before entering the mouth of the user.

15 It will be noted that by reason of the construction and arrangement shown and described, the admission of air to the smoke duct or chamber 12 is controlled directly by and in proportion to the temperature of the smoke within the duct as it passes to the mouth piece of the pipe, and that 20 by positioning the thermostat within the smoke duct, the thermostat is fully protected against the influence of outside atmospheric temperature conditions, thereby providing ample assurance of the continued efficient operation of the 35 thermostat for controlling the passage of air into the chamber 12 in accordance with the temperature of the smoke therein.

25 As previously mentioned, the mouth piece 14 and elements mounted thereon may be manually rotated within the stem 11, and by reference to Fig. 5, it will be noted that by rotating the mouth piece, preferably, through an arc of 180°, the end portion 25 of the thermostat will be removed from adjacent the inlet port 22, thereby rendering the thermostat ineffective to admit air to the chamber 12, in which event, a pipe embodying features of the present invention, may, if desired, be used as an ordinary pipe. Thus, it will be observed that by such an arrangement, the 45 admission of air through the port 23 may be manually, as well as automatically, controlled.

30 It will be observed from the foregoing description that the present invention provides a novel construction and arrangement whereby air may be admitted to the smoke ducts or passages for cooling the smoke before reaching the mouth of the user, and wherein the admission of air is automatically controlled by thermostatically actuated means, which, if desired, may be rendered 35 inoperative at the will of the user; also, that the present invention provides a construction and arrangement whereby moisture may be removed from the smoke passages before entering the mouth piece, thereby providing a cool, dry smoke.

40 Obviously, the present invention is not limited to the precise construction and arrangement shown and described as the same may be variously modified. Moreover, all the features of the invention need not be used conjointly as the same 45 may be used to advantage in variously different combinations and sub-combinations.

45 What I claim as new and desire to secure by Letters Patent is:

50 1. In a smoking pipe comprising a bowl and a stem therefor having a smoke duct formed in

said stem, the combination of an air intake valve having an opening communicating with said duct for admitting air thereto, a closure for said opening and a thermostat in said smoke duct operatively related to said valve closure for controlling 5 the passage of air to the duct.

2. In a smoking pipe comprising a bowl, a stem therefor having a smoke duct formed therein, said stem having an air intake port formed therein communicating with said duct, and a thermostatically actuated valve positioned in the smoke duct and operatively related to said port for controlling the passage of air therethrough.

3. In a smoking pipe comprising a bowl, a stem therefor having a smoke duct formed therein, 15 said stem having an air intake port formed therein communicating with said duct, and a thermostatically actuated valve carried by a portion of said stem within said smoke duct and operatively related to said port for controlling the passage of 20 air therethrough.

4. In a smoking pipe comprising a bowl, a stem therefor having a smoke duct formed therein, said stem having an air intake port formed therein and communicating with said duct, a valve in 25 said smoke duct operatively related to said port for controlling the passage of air therethrough, and a thermostat in said smoke duct and operatively related to said valve for controlling the position thereof in accordance to the temperature 30 of smoke in said duct.

5. In a smoking pipe comprising a bowl, a stem therefor having a smoke duct formed therein communicating with said bowl, said stem having an air intake port formed therein at one side 35 thereof communicating with said duct, and a thermostat in said smoke duct operatively related to said port for controlling the passage of air therethrough.

6. In a smoking pipe comprising a bowl, a stem 40 therefor having a smoke duct formed therein and having an air intake port communicating with said duct, a mouth piece extending into said duct, and a thermostat mounted on said mouth piece in said duct and operatively related to said port for controlling the passage of air therethrough into said smoke duct.

7. In a smoking pipe comprising a bowl, a stem therefor having a smoke chamber formed therein communicating with said bowl and having an air intake port communicating with said chamber, a mouth piece extending into said chamber, and a thermostat mounted adjacent one of its ends on said mouth piece in said chamber and operatively related adjacent its opposite end to 50 said port for controlling the passage of air therethrough into said smoke chamber.

8. In a smoking pipe comprising a bowl, a stem therefor having a smoke chamber formed therein communicating with said bowl and having an open end portion and an air intake port communicating with said chamber, a mouth piece extending into said chamber and comprising a portion of reduced diameter positioned in the open end portion of the chamber and an elongated finger extending into the chamber, and a thermostat mounted on said finger and operatively related to said port for controlling the passage of air therethrough into said chamber.

9. In a smoking pipe comprising a bowl, a stem 70 therefor having a smoke chamber formed therein communicating with said bowl and having an open end portion and an air intake port communicating with said chamber, a mouth piece extending into said chamber and comprising a 75

portion of reduced diameter positioned in the open end portion of the chamber and an elongated tubular finger having an opening therein at one side thereof and extending into said chamber, and a thermostat mounted on said finger adjacent said opening and operatively related to said port for controlling the passage of air therethrough into said chamber.

10. In a smoking pipe comprising a bowl, a stem therefor having a smoke chamber formed therein communicating with said bowl and having an open end portion and an air intake port communicating with said chamber, a mouth piece extending into said chamber and comprising a portion of reduced diameter positioned in the open end portion of the chamber and an elongated tubular finger having an elongated opening therein at one side thereof and extending into said chamber, and a thermostat mounted at one of its ends on said finger and extending along the open side thereof into said recess and into operative relationship with respect to said port for controlling the passage of air therethrough into said chamber.

11. In a smoking pipe comprising a bowl, a stem therefor having a smoke chamber formed therein communicating with said bowl and having an open end portion and an air intake port adjacent said open end portion communicating with said chamber, a mouth piece extending into said chamber and comprising a portion of reduced diameter having a recess formed therein adjacent said port and mounted in the open end portion of said chamber, an elongated tubular finger extending into said chamber and having an open side portion, and a thermostat mounted at one of its ends on said finger and extending along the open side thereof into said recess and into operative relationship with respect to said port for controlling the passage of air therethrough into said chamber.

12. In a smoking pipe comprising a bowl, a stem therefor having a smoke chamber formed

therein communicating with said bowl and having an open end portion and an air intake port adjacent said open end portion communicating with said chamber, a mouth piece extending into said chamber and comprising a portion of reduced diameter having a recess formed therein adjacent said port and rotatably mounted in the open end portion of said chamber in a manner to cover and uncover said port when said mouth piece is rotated with respect to said stem and an elongated tubular finger extending into said chamber and having an open side portion, and a thermostat mounted at one of its ends on said finger and extending along the open side thereof into said recess and into operative relationship with respect to said port for controlling the passage of air therethrough into said chamber.

13. In a smoking pipe comprising a bowl, a stem therefor having a smoke chamber formed therein communicating with said bowl and having an open end portion and an air intake port adjacent said open end portion communicating with said chamber, a mouth piece extending into said chamber and comprising a portion of reduced diameter having a radially extending recess formed therein adjacent said port and rotatably mounted in the open end portion of said chamber in a manner to cover and uncover said port when said mouth piece is rotated with respect to said stem and an elongated tubular finger extending into said chamber in spaced relation to the walls thereof and having an open side portion and an aperture at the side thereof opposite said open portion, and a thermostat mounted at one of its ends on the inner end portion of said finger and extending along the open side thereof into said recess and into operative relationship with respect to said port for controlling the passage of air therethrough into said chamber.

ARTHUR B. MODINE.
